[57] CLAIM

The ornamental design for a scooter, as shown and described.

DESCRIPTION

FIG. 1 is a top perspective view of a scooter. FIG. 2 is a front view showing my new design. FIG. 3 is a rear view showing my new design. FIG. 4 is a right side view showing my new design. FIG. 5 is a bottom view showing my new design; and, FIG. 6 is a top view showing my new design. The left side of my new design is a mirror image of FIG. 4. The name and illustration of the “road runner” forming part of the claimed design is a registered trademark of Time Warner Entertainment Company.
